KATHERINE A. LUCEY Inventor

By *Richard B. Duren* Attorney

UNITED STATES PATENT OFFICE.

KATHERINE A. LUCEY, OF MAZOMANIE, WISCONSIN.

BRUSH.

Application filed March 3, 1924. Serial No. 696,663.

To all whom it may concern:

Be it known that I, KATHERINE A. LUCEY, citizen of the United States, residing at Mazomanie, in the county of Dane and State 5 of Wisconsin, have invented certain new and useful Improvements in Brushes, of which the following is a specification.

The present invention relates to brushes and aims to improve upon the structure 10 thereof so as to provide a device which will be efficient in cleansing milk cans and the like.

Another important object of the invention is to provide a device of this nature having 15 a resilient mounting so that the bristles thereof may be forced into engagement with all parts of the can being cleaned.

A still further object of the invention is to provide a brush of this nature having 20 a simple structure, one which is reliable, inexpensive to manufacture, durable, light, and well adapted to the purpose for which it is designed.

With the above and numerous other objects in view as will appear as the description progresses, the invention resides in certain novel features of construction, and in the combination and arrangement of parts 25 as will be hereinafter more fully described and claimed.

In the drawing:

Figure 1 is an elevation of a brush embodying my invention, and

Figure 2 is a perspective view of one of 35 the spring arms forming a part of the brush.

Referring to the drawing in detail, it will be seen that 1 designates an elongated handle formed of any desirable material and 40 provided at one end with a suitable hook 2 so that it may be engaged with a nail when the brush is not in use. A pair of spring arms 3 is disposed on the other end of the handle 1. Each spring arm 3 is curved 45 throughout its length terminating at one end in a pair of oppositely disposed ears 4 which are curved over toward each other to form a sleeve. The other end of the arm is provided with an eye or opening 5. A bolt, 50 screws, or other fastening elements 6 pass through the eyes or openings 5 of the arms 3 so as to secure them to the end of the handle 1 in such a manner that they are curved from each other as is indicated to advantage 55 in Figure 1. The brush proper indicated at A comprises a twisted wire shank 7 pref-

erably formed of two strands of wire twisted about each other. These wires are formed of some suitable resilient material and the ends thereof are disposed in and held by the sleeves formed by the ears 4. The intermediate portion *b* of the shank 7 is substantially straight while the end portions *c* are curved toward each other so that the terminals *d* may be received within the sleeve formed by ears 4. The arms 3 are also formed of some resilient material and it will thus be seen that by pressing downwardly upon the handle 1 the length of the straight intermediate portion *b* may be increased since the curved portion *c* will be forced outwardly and portions thereof become continuations of the intermediate portion *b*. It will also be seen that because of the resilient nature of the arms 3 of the shank 7 that the brush may be forced 70 through a rather restricted neck of a milk can and used to efficiently clean the bottom thereof.

The bristles *f* are preferably attached in intermediate their ends by being passed between the two twisted strands of the shank 7 and should be comparatively stiff so that they may be forced into the crevices of cans and the like. Although I have described 80 my invention with a certain degree of particularity, it is to be understood that numerous changes in the details of construction, and in the combination and arrangement of parts may be resorted to without departing 85 from the spirit or scope of the invention as hereinafter claimed or sacrificing any of its advantages.

Having thus described my invention, what I claim as new is:

1. A brush of the class described including a handle, a pair of resilient arms extending from one end of the handle and curved so as to diverge from each other and terminating in sleeves, a bristle carrying 100 member, a wire shank having its ends disposed in and engaged by said sleeves.

2. A brush of the class described including a handle, a pair of curved arms attached to the handle and diverging from each other 105 and terminating in a pair of oppositely disposed ears curved over toward each other to form sleeves, and a bristle carrying member having a resilient wire shank, the ends thereof being disposed in and engaged by 110 the ears forming the sleeves.

3. A brush of the class described includ-

ing a handle, a pair of resilient arms, each arm being curved throughout its length and terminating at one end in a pair of oppositely disposed ears curved toward each other to form a sleeve and at its other end an opening, fastening elements passing through the openings of the arms for attaching them to the handle, said arms diverging from each other when attached to the handle, and a
10 bristle carrying member including a wire

shank of resilient material, the ends of the wire shank being received in and engaged by the sleeves formed by the ears.

In testimony whereof I affix my signature in presence of two witnesses.

KATHERINE A. LUCEY.
